UNITED STATES PATENT OFFICE.

ALBERT L. HARVEY, OF WILKINSBURG, PENNSYLVANIA, ASSIGNOR TO WESTINGHOUSE ELECTRIC & MANUFACTURING COMPANY, A CORPORATION OF PENNSYLVANIA.

MOTOR-CONTROL SYSTEM.

Application filed February 20, 1923. Serial No. 620,129.

My invention relates to motor-control systems and it has particular relation to control systems subject to considerable variation in line voltage.

5 The object of my invention is to afford suitable protection to motors subjected to sudden increase in current, particularly in the armature circuit, by reason of fluctuations in voltage.

10 In such applications as mine gathering pumps, the voltage condition are often very bad on account of the fact that power is usually obtained from railway circuits. As a result of such fluctuations in voltage, current variations are produced in accordance 15 with Ohm's law,

$$I = \frac{E}{R}$$

20 in which E is equal to line voltage minus the counter-electromotive force of the motor connected thereto and R is the resistance of the conductors leading to the motor plus the internal resistance of the motor armature.

25 At the present time a large number of pumping outfits are driven by self-starting direct-current motors. That is to say, no controller or automatic starter is employed. In order, therefore, to protect the motor, 30 when running normally, against fluctuations in current caused by changes in impressed voltage, it is common practice to permanently connect a resistor, such as a water rheostat, in the armature circuit.

35 To avoid the use of a permanent external resistor I propose to employ automatic electroresponsive means for inserting a resistor in the armature circuit during periods of abnormal voltage and to remove said resistor 40 from circuit upon the restoration of normal voltage conditions.

My invention will be best understood by reference to the accompanying drawing in which the single figure is a diagrammatic 45 view of circuits and apparatus embodying my invention.

With reference to the drawing, a motor having an armature 1, a shunt field-magnet winding 2 is operatively connected to line conductors 4 and 5 through an auxiliary resistor 6. An electromagnetic switch 7 is arranged for controlling resistor 6 and is provided with an operating coil 8. An auxiliary relay 11 is adapted to control switch 7 and is provided

with operating coils 12 and 13. The energizing circuit of coil 13 is normally interrupted by a condenser 10, the purpose of which will be hereinafter described.

In order that the advantages of my invention and the necessity for such protection may be more readily understood, it may be assumed that 550 volts is the normal line voltage. It may also be assumed that, by reason of varying load conditions in a railway circuit, the voltage fluctuates between a maximum of 600 60 volts and a minimum of 450 volts. If, at one instant, the motor is operating in accordance with a line potential of 450 volts and is developing a counter-electromotive force of say 400 volts, the effective voltage impressed on 65 the armature is 50 volts and, if the resistance R is equal to 1 ohm a current of 50 amp., according to the above-mentioned formula, traverses the armature 1.

Now suppose at the next instant, the railway load is suddenly lifted and the line voltage rises to 600 volts. Before it is possible for the motor to accelerate and develop additional counter-electromotive force, there is an instantaneous voltage impressed on the armature equal to 600 volts minus the 400 volts counter-electromotive force. R being a constant the momentary armature current is 200 70 amp., which is the result of impressing an effective voltage upon the armature equal to 80 400 volts. It is well understood that such a fluctuation in current is very undesirable and it is the purpose of my invention to limit the current to a safe value.

90 In accordance with my invention, I employ a relay 11 that is relatively small and may be designed to respond readily to fluctuations in voltage and current. The operating or current coil 12 is preferably connected in the 95 circuit of armature 1, and a voltage coil 13 is connected in circuit with condenser 10. Coils 12 and 13 are commonly termed "series" and "shunt", respectively.

When normal voltage obtains in line conductors 4 and 5, switch 7 is closed, its operating coil 8 being fed through relay 11 from conductors 4 and 5. Upon the occurrence of abnormal voltage sufficient to charge condenser 10, coil 13 will be energized to such an extent 105 that it will assist series coil 12 to actuate relay 11, thereby interrupting the circuit through coil 8 and effecting the opening of switch 7

for the purpose of inserting resistor 6 in circuit with armature 1, thereby limiting the motor current as will be readily appreciated.

When normal voltage is restored, condenser

- 5 10 discharges its energy to deenergize coil 13 and, as soon as normal current flows in the circuit of armature 1, the excitation of coil 12 is sufficiently reduced to release and restore relay 11 to its illustrated position, whereupon
- 10 switch 7 is reclosed.

According to my system, the use of a permanently connected resistor becomes unnecessary, and the effect of a condenser as herein employed serves to insure a positive and quick 15 operation of the protective apparatus, automatically, in accordance with the value of voltage impressed upon the motor.

I claim as my invention:

1. In a protective system the combination 20 with a motor having an armature, of a resistor connected in circuit therewith, a switch for controlling said resistor, electroresponsive means for controlling said switch, and means comprising a coil and a condenser in circuit

therewith for rendering the electroresponsive 25 means effective upon sudden variations in voltage.

2. In a protective system the combination with a motor having an armature, of a resistor therefor, a switch for controlling said 30 resistor, a series coil for controlling said switch, a second coil for assisting the series coil, and a condenser for controlling said second coil in accordance with sudden variations in voltage impressed upon said motor. 35

3. The combination with a motor having an armature, of a protective resistor therefor, a switch for controlling said resistor, a relay for controlling said switch having an operating coil responsive to the motor armature current, a coil for assisting said relay coil, and a condenser for controlling the last named coil in accordance with sudden variations in voltage impressed upon said motor. 40

In testimony whereof, I have hereunto subscribed my name this 14th day of February, 45 1923.

ALBERT L. HARVEY.
